UNITED STATES PATENT OFFICE

101,066

DESIGN FOR A COMBINATION PENCIL AND PAD HOLDER

William B. Richardson, Washington, D. C.

Application June 17, 1936, Serial No. 63,342

Term of patent 7 years

To all whom it may concern:

Be it known that I, William B. Richardson, a citizen of the United States, residing at Washington, District of Columbia, have invented a new, original, and ornamental Design for a Combination Pencil and Pad Holder, of which the following is a specification, reference being had to the accompanying drawing, forming part thereof.

Figure 1 is a perspective view of a combination

pencil and pad holder, showing my new design, and

Figure 2 is a top plan view thereof.

I claim:

The ornamental design for a combination pencil and pad holder, as shown.

In testimony whereof I affix my signature.

WILLIAM B. RICHARDSON.
